[57] CLAIM

The ornamental design for a hat and glove rack, as shown and described.

DESCRIPTION

FIG. 1 is a top and front perspective view of a hat and glove rack showing my new design;
FIG. 2 is a front elevational view thereof, the rear being a mirror image of that shown;
FIG. 3 is a side elevational view thereof, the opposite side being a mirror image of that shown;
FIG. 4 is a top plan view thereof;
FIG. 5 is a bottom plan view thereof;
FIG. 6 is a top and front perspective view of a second embodiment of a hat and glove rack showing my new design;
FIG. 7 is a front elevational view thereof;
FIG. 8 is a side elevational view thereof, the opposite side being a mirror image of that shown;
FIG. 9 is a rear elevational view thereof;
FIG. 10 is a top plan view thereof;
FIG. 11 is a bottom plan view thereof;
FIG. 12 is a top and front perspective view of a third embodiment of a hat and glove rack showing my new design;
FIG. 13 is a front elevational view thereof, the rear being a mirror image of that shown;
FIG. 14 is a side elevational view thereof, the opposite side being a mirror image of that shown;
FIG. 15 is a top plan view thereof; and,
FIG. 16 is a bottom plan view thereof.
